(57) CLAIM

The ornamental design for an item of jewelry, as shown and described.

DESCRIPTION

FIG. 1 is a front view of an item of jewelry showing my new design;

FIG. 2 is a back view of the embodiment of FIG. 1; and, FIG. 3 is a side view of the embodiment of FIG. 1.

The broken lines in the drawings illustrate environmental structure of the item of jewelry that form no part of the claimed design.

1 Claim, 3 Drawing Sheets

FIG. 1

FIG. 3
